INVENTOR
HELEN E. MILLER

BY *Cushman, Darby & Cushman*

ATTORNEY

the garment is gathered to and secured to an elastic band 20, in any suitable fashion. While an elastic band is preferred, any equivalent means, such as a drawstring, may be employed. The leg openings of the garment may similarly be edged with elastic, as shown, or may be merely hemmed or otherwise secured against unravelling.

In use, the garment is readily drawn on into position, the elastic band being expanded over the abdomen and then emplaced thereabove at the natural waistline, as shown in Figure 1. It will be readily apparent from the drawing that the pantie exerts no restrictive pressure whatsoever on the abdomen, but is retained in place solely by the light pressure of the elastic band exerted thereabove, in an inward and slightly downward direction. The side seams 18, being of fixed length, pull the sides of the elastic band downwardly from the elevated position of the front portion thereof, whereby the band fits substantially straight across the back.

By reason of the greater length and width of the front panel, and the gathering 19, the front of the garment is especially adapted to fit about the figure of the wearer without the slightest discomfort or restriction. When the garment is constructed of ordinary underwear knit, as will usually be the case, the natural give of the material further tends to accommodate the garment to the figure of the wearer. Additionally, the garment fits with pleasing smoothness, an effect enhanced by the bowed upper edge 15 of the front panel, shown in Figure 3. In place, it will be noted, the excess width of the front panel is extended about the figure of the wearer, and the side seams 18 are drawn in this manner to a normal position on the hips.

The garment is obviously not limited in utility to cases of pregnancy, but may be worn at any time by women whose figures are suited thereto.

It will thus be seen that there has been provided by this invention a structure in which the various objects hereinbefore set forth, together with many practical advantages, are successfully achieved. As various possible embodiments may be made of the mechanical features of the above invention, all without departing from the scope thereof, it is to be understood that all matter hereinbefore set forth or shown in the accompanying drawings is to be interpreted as illustrative, and not in a limiting sense.

I claim:

1. A maternity pantie comprising a front panel and a back panel joined by a crotch portion, said front panel being smooth and substantially longer and wider than said back panel, said front and back panels being joined to each other in side

seams, the upper portion of said front panel being gathered into said side seams.

2. A maternity pantie comprising a front panel and a back panel joined by a crotch portion, said front panel being smooth and substantially longer and wider than said back panel, said front and back panels being joined to each other in side seams, the upper portion of said front panel being gathered into said side seams, and means associated with the upper edge of said pantie for varying the opening thereof.

3. A maternity pantie comprising a front panel and a back panel joined by a crotch portion, said front panel being smooth and substantially longer and wider than said back panel, said front and back panels being joined to each other in side seams, and resilient means associated with the upper edge of said pantie for varying the opening thereof.

4. A maternity pantie comprising a front panel and a back panel joined by a reinforced crotch portion, said front panel being smooth and substantially longer and wider than said back panel, said front and back panels being joined to each other in side seams, the upper portion of said front panel being gathered into said side seams, the upper edge of said pantie being at least partially gathered into an elastic band.

5. A maternity pantie comprising a front panel and a back panel joined by a crotch portion, said front panel being smooth and substantially longer and wider than said back panel, the upper edge of said front panel being bowed, said front and back panels being joined to each other in side seams, the upper portion of said front panel being gathered into said side seams.

6. A maternity pantie comprising a front panel and a back panel joined by a crotch portion, said front panel being smooth and substantially longer and wider than said back panel, the upper edge of said front panel being bowed, the front and back panels being joined to each other in side seams, the upper portion of said front panel being gathered into said side seams, and means associated with the upper edge of said pantie for varying the opening thereof.

HELEN E. MILLER.
